UNITED STATES PATENT OFFICE.

THOMAS FERGUSON, OF EDINBURGH, SCOTLAND.

DESIGN FOR A LAMP.

SPECIFICATION forming part of Design No. 24,737, dated October 8, 1895.

Application filed April 10, 1895. Serial No. 545,254. Term of patent 14 years.

To all whom it may concern:

Be it known that I, THOMAS FERGUSON, ironmonger, a subject of the Queen of Great Britain and Ireland, and a resident of No. 17 West Maitland Street, Edinburgh, Scotland, have invented and produced a new and original Design for Lamps, of which the following is a specification, reference being had to the accompanying drawings, forming a part thereof.

Figure 1 is a side elevation of a lamp, showing my design. Fig. 2 is a top view thereof. Fig. 3 is a bottom view of the same.

The leading features of my design consist in a globular head, a globular pendant, outwardly-bowed branches extending from the head to the pendant, and radial arms extending from the pendant between the branches.

A represents a support carrying a globular head B, from which extend outwardly-bowed branches C, connected with a globular pendant D, having radial arms E, extending outwardly from between the arms, so as to simulate a cage-figure in side elevation and a star-figure in bottom view. 20

Having thus described my invention, the following is what I claim as new therein and desire to secure by Design Letters Patent:

The design for a lamp substantially as herein shown and described. 25

THOMAS FERGUSON.
